Karl Michels
INVENTOR
BY Victor J. Evans
ATTORNEY

UNITED STATES PATENT OFFICE

KARL MICHELS, OF MUSCATINE, IOWA

RESPIRATOR

Application filed January 24, 1930. Serial No. 423,215.

This invention relates to a respirator, the general object of the invention being to provide means for improving the lungs and other parts of the respiratory system of the human body through means of drawing air into the lungs, while causing the air to pass through water or other liquid so that the greater effort required to draw the air through the water exercises the parts.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is an elevation of the invention.

Figure 2 is a plan view of the holder.

Figure 3 is a plan view of the device.

In these views, the letter A indicates a holder which is composed of the base 1, the upright 2 having a ring 3 at its upper end and the holder rings 4 which are attached to opposite sides of the upright by the stems 5.

Receptacles 6 pass through the rings 4 and rest upon the base and a stopper 7 closes each receptacle. A pipe 8 has its upper end arranged in a hole in each stopper with its lower end terminating short of the bottom of the receptacle. An inverted U-shaped pipe 9 has its ends located in holes in the stoppers and a nipple at the upper end of the pipe 9 is connected by a tube or hose 10 with a mouth piece 11.

Thus by placing water or other liquid in the receptacles and then placing the mouth piece in the mouth and inhaling, the air is drawn through the water in the receptacles and into the lungs and as the water offers a resistance to the passage of the air, the lungs and other parts of the respiratory system will be exercised.

The receptacles may be provided with graduations so that any desired amount of liquid can be placed in the receptacles ac-

cording to the resistance to the passage of air desired.

The following directions for the use of the device are given to insure proper use thereof:—

Put rubber hose firmly on small tube. Put water in first bottle to suit individual case in accordance with printed instructions. Put in second bottle solution of $\frac{1}{4}$ of 1% mercurochrome, same amount as in first bottle.

Regulate amount of water to suit one's need. For weak lungs, an inch or two will suffice. Increase amount of water as lungs develop. Renew water at least once a week.

Put cork tight into neck of bottle.

Stand the device on floor, window sill or table, wherever convenient.

Stand with back against wall, head erect.

Put loose end of hose connected with mouth piece in mouth.

Inhale air through tube as deeply as possible and exhale through nose. Continue same for ten minutes.

Use device at least twice a day; mornings and before retiring for the night.

Pin towel or fasten wide strap conveniently tight around chest and breathe energetically against them.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A respirator comprising an elongated base, fluid containing receptacles positioned on said base, a vertical stem carried by said base intermediate the ends thereof and extending upwardly between the receptacles with the upper end enlarged to provide a finger grip disposed above said receptacles, a pair of retaining members carried by the stem and encircling the receptacles to prevent displacement of the latter from the base, closures for said receptacles, tubes extending through the closures and terminating adjacent the bot-

toms of the receptacles, and an inverted **U**-shaped tube extending through the closures and straddling the finger piece of the stem,
5 a nipple on the **U**-shaped tube, a flexible tube connected to the nipple and the mouth piece connected to the flexible tube.
